JEWELRY DISPLAY EASEL

John Sands, 4757 Aldrich Ave. S., Minneapolis, Minn.

Filed Oct. 4, 1960, Ser. No. 62,372

Term of patent 3½ years

(Cl. D80—9)

FIG. 1

FIG. 2

FIG. 3

FIG. 4

FIG. 1 is a view in perspective showing my new jewelry display easel;

FIG. 2 is a view in rear elevation thereof;

FIG. 3 is a view in side elevation thereof as seen from left to right of FIG. 2; and

FIG. 4 is a view in bottom plan thereof.

The side opposite that shown in FIG. 3 is a mirror image of that shown in FIG. 3.

I claim:

The ornamental design for a jewelry display easel, as shown and described.
